EGG SHIPPING CASE

Reynolds Guyer, St. Paul, Minn., assignor to Wal-
dorf Paper Products Company, St. Paul, Minn.,
a corporation of Minnesota

Application January 2, 1951, Serial No. 203,996

1 Claim. (Cl. 229—23)

1 My invention relates to an improvement in egg case wherein it is desired to provide a simple case for eggs and the like which may be shipped in a flat condition and easily erected by the consumer.

One of the difficulties experienced in the sale of egg cases lies in the fact that some type of equipment is usually required to erect the cases. Usually it is necessary to either glue or stitch the parts together when the case is erected. The present invention deals with a type of case which may be shipped flat and which may be easily put together without requiring equipment.

An object of the present invention lies in the provision of an egg case having an outer shell and a lining member designed to extend into the shell. The outer shell comprises a rectangular structure having opposed side and end walls connected in tubular relation. The liner comprises a pair of members connected together which form a double bottom in the case and which form lining panels for all of the walls of the outer shell.

A feature of the present invention lies in the provision of a lining member for an egg case, which includes an elongated strip of paper board or the like including a series of panels foldably connected together and designed to form a container bottom, container end wall lining panels, container top panels, and tuck flaps on the top panels. The tuck member comprises a strip of material secured at right angles to the base of the first strip and includes a bottom panel stitched or otherwise secured to the bottom panel of the first strip and a pair of side wall panels foldably connected to the bottom panel. When placed in the case, a liner is provided for all of the container walls and a container top is also provided.

These and other objects and novel features of my invention will be more clearly and fully set forth in the following specification and claim.

In the drawings forming a part of my specification:

Figure 1 is a perspective view of my egg case showing in general the construction thereof.

Figure 2 is a perspective view of the outer shell of the egg case.

Figure 3 is a plan view of the liner in flat condition.

Figure 4 is a perspective view of the partition forming unit.

Figure 5 is a longitudinal section through the container.

Figure 6 is a transverse section through the container.

The container includes an outer shell 10, a lin-

ing member 11 and a partition unit 12. These parts assembled together form the completed egg case.

The outer shell 10 includes a side wall panel 13 foldably connected at 14 to an end wall panel 15. The panel 15 is secured at a fold line 16 to the side wall 17. The side wall 17 is connected along a fold line 19 to an end panel 20. The panel 20 is connected to an edge of the panel 13 by tape 21 or other suitable connecting means.

A transverse line of fold 22 is provided at the upper ends of all of the wall panels. This line of fold connects the wall panels to the closing and reinforcing flaps. The fold line 22 connects the panel 13 to a pair of spaced closing flaps 23 and 24 spaced by a center slot 25. The fold line 22 connects the end panel 15 to a reinforcing flap 26. The fold line 22 also connects the panel 17 to a pair of spaced closing flaps 27 and 29 which are spaced by a slot 30 mid-way between the ends of the case. The panel 20 is connected along the fold line 22 with the reinforcing flap 31.

The flaps 26 and 29 are foldable down to lie adjacent the upper portions of the panels 15 and 20 to which they are hinged. A hand hole 32 is provided in each end wall just below the flaps 26 and 31 in inwardly folded condition thereof. The liner includes two strips connected together at right angles. The first strip includes a bottom panel 33 connected along lines of folds 34 and 35 to end wall panels 36 and 37. These wall panels are connected along fold lines 39 and 40 to top panels 41 and 42. The top panels are connected along fold lines 43 and 44 to tuck flaps 45 and 46.

Hand holes 47 are provided in the panels 36 and 37, these hand holes registering with the hand holes 32 in the outer shell when the liner is in place. The liner 11 also includes a second strip including a bottom panel 49 connected along fold lines 50 and 51 to inner side wall panels. The bottom panel 49 is connected along the fold line 50 to a pair of spaced panels 52 and 53 which are spaced by a slot 54. The bottom panel 49 is likewise connected along the fold line 51 to a pair of spaced panels 55 and 56 which are spaced by a slot 57. The slots 54 and 57 are aligned in flat condition of the liner and are at the center of the case in preferred form. Stitches 59, or other suitable connecting means hold the two lining portions in proper relation.

In Figure 4 of the drawings, I disclose the partition unit 12. This unit includes a pair of panels 60 and 61 which are connected along the bottom fold line 62. Anchoring flanges 63 and 64 are connected to one end of the panels 60 and 61 and

55

similar anchoring flanges 65 and 66 are provided at the other end of these panels. The anchoring flanges are foldable relative to the partition panels 60 and 61 and may extend at right angles thereto as shown in Figure 4.

The case thus formed is shipped in a flat condition and in three different parts. When it is desired to assemble the case, the outer shell 10 is folded into the rectangular form illustrated in Figure 2 of the drawings. The liner 11 is next inserted into the shell 10, the end wall panels 36 and 37 being folded upwardly at right angles to the bottom panels and the side wall panels 52, 53, 55 and 56 being folded upwardly to lie inwardly of the side walls of the shell. The partition unit 12 is next inserted into the case. The anchoring flanges 63 and 64 extending between portions of the liner panels 52 and 53 and the corresponding side wall 17 and the other anchor flanges 65 and 66 lying between the wall panels 55 and 56 and the corresponding shell side wall 13. The egg case is then in condition to be filled. When the case has been filled the cover panels 41 and 42 are hinged downwardly and the tuck flaps 45 and 46 inserted into the space between the panels 60. Before folding the top panels downwardly, the closing flaps 23, 24, 27, and 29 are folded into horizontal position. These grooved flanges tend to lock the liner in place within the shell. Furthermore, when the case is carried the hands extend through the hand holes 32 and also the hand holes 47, thereby holding the parts together.

In accordance with the patent statutes, I have described the principles of construction and operation of my egg case, and while I have endeavored to set forth the best embodiment thereof, I desire to have it understood that obvious changes may be made within the scope of the following claim without departing from the spirit of my invention.

I claim:

An egg case including an outer bottomless shell

comprising a series of side and end walls connected together in rectangular relation, a liner including a series of panels foldably connected together and insertable into the shell, the liner including a first bottom panel, end wall panels hingedly connected to opposite ends of said bottom panel, and cover panels hingedly secured to the ends of said end walls, a second bottom panel in surface contact with the first bottom panel and secured thereto, side wall panels foldably connected to said second bottom panel, opposed vertical slots in said side wall panels, the side walls of said outer shell having flaps hingedly secured thereto, said flaps being engageable beneath said cover panels in assembled form of the case, the cover panels including means for holding the same in a common plane, and a partition member vertically slidable through said slots and including anchoring portions slidable between said side wall panels and the side walls of said outer shell.
